UNITED STATES PATENT OFFICE.

GEORGES EZBELENT AND ROGER EZBELENT, OF PARIS, FRANCE.

CAM DEVICE.

Application filed June 28, 1926, Serial No. 118,814, and in France March 17, 1926.

This invention relates to a controlling device operating by cam and lever for use upon machines for treating textile fabrics, for instance upon pleating machines, for the control of the inclination of the knives or of the automatic spacing means. According to this invention the cam cooperating with the control lever and which is given a suitable movement, consists of two discs between which are disposed rollers each of which is mounted upon an eccentric portion of an axle pin and the said control lever is caused to bear upon the cam through the medium of an eccentric roller whose position is adjustable.

Due to the said device the amount of the oscillation of the lever produced by the rotation of the cam in contact therewith can be very readily modified, and for this purpose it will be sufficient to give a suitable rotation to the eccentric parts of the said axle-pins, and the position of the lever may further be changed without interfering with the rollers of the said cam; to this end it is simply necessary to give a suitable rotation to the eccentric roller by means of which the lever is caused to bear upon the cam.

Further characteristics of the invention will be set forth in the following description.

In the appended drawings which are given solely by way of example:

Fig. 1 is an elevation, with parts broken away, of a cam and lever device in accordance with the invention.

Fig. 2 is a section on the line A—A of Fig. 1.

Fig. 3 is a partial view of the cam showing an arrangement by which the axle pins of the rollers are held in a given angular position.

In the device illustrated, the cam consists of two discs 1 and 2 which are secured together and on which are mounted a plurality of axle-pins 3 having an eccentric portion *a*. Rollers 4 are loosely mounted on the eccentric parts *a* and form bosses which act during the rotation of the cam upon the controlling lever 5 which is pivoted at 6 and makes contact with the cam by means of the eccentric roller 7.

At one end of each axle-pin 3 is a cross-pin 8 coacting with a slot 9 in the disc 1, which maintains the axle-pin and its eccentric part in position, so that the roller may protrude or not from the periphery of the disc.

The pin 8 is held in place in the slot 9 by the spring 11 which bears at one end against the disc 2 and at the other against the head or knob 12. The head 12 serves to actuate the corresponding axle-pin 3; to change the position of the eccentric part *a*, the head 12 is pushed in such manner as to overcome the action of the spring 11, so that the axle-pin 3 will slide and the pin 8 will leave the slot 9; the pin 3 can then be turned through 180 degrees, and then, by releasing the head 12, the pin 8, when urged by the spring 11, will again enter the slot 9 and will hold the axle pin 3 in this new position. To allow of pushing the axle pin 3 for disengaging the pin 8 from the slot 9, a gap 13 is left between the disc 1 and the eccentric part *a*.

The amount of eccentricity of the roller 7, by which the lever 5 makes contact with the said cam, is regulated by a device analogous to what has been described for the rollers 4 of the cam, but in order to give this roller a position corresponding to an intermediate projection between the maximum and minimum, an additional slot 10 is formed at right angles to the slot 9, coacting with the pin 8.

When employing the above described device for the control of the position of the knives of an ordinary pleating machine, the lever 5 being then connected with the said knives, the axle-pins 3 are so turned that the corresponding rollers 4 will assure the formation of a high pleat or a low pleat, according as the lever 5—during the rotation of the cam—meets or not with a boss formed by a roller 4 which projects outwardly due to the position of the eccentric on which it is mounted: the knives are thus brought into contact with the upper formation plate or with the lower formation plate. It will be further noted that by changing the position of the eccentric roller 7 so as to move the lever 5 towards or from the axis of the cam, pleats of different nature may be obtained due to the change in the position of the lever; the roller 7 can be differently set while the machine is running, without changing the position of the cam rollers.

In the case in which the said device is employed upon a pleating machine comprising sections of formation plates which may cross between the machine rollers, and when it is desired to operate the knives according to the line bisecting the angle between

the formation plates, it will be sufficient to change the position of the eccentric roller 7 by placing its axle-pin in the intermediate position, so that the knives will take an intermediate position between their upper position and their lower position.

Obviously, the present invention is not limited to the construction herein described which is given solely by way of example, 10 and the apparatus is susceptible of various detail modifications without departing from the principle of the invention. In like manner, the said invention is applicable to other types of machines, such as ruching, crimping, 15 goffering and like machines.

Having now described our invention, what we claim as new and desire to secure by Letters Patent is:

1. Cam device comprising a disc, a number 20 of axle pins rotatably and slidably supported by said disc near the periphery thereof, an eccentric part on each of said axle-pins, a roller mounted loose on said eccentric part and means for maintaining each 25 axle-pin in various angular positions for which said rollers protrude to a variable amount from the periphery of the disc.

2. Cam device comprising a disc, a number 30 of axle-pins rotatably and slidably supported by said disc near the periphery thereof, an eccentric part on each of said axle-pins, a roller mounted loose on said eccentric part, a cross-pin provided on each axle-pin, slots in said disc and wherein said cross-pins are respectively adapted to engage and 35 springs acting axially upon said axle pins and whereby said cross-pins are urged into said slots for holding said axle-pins in position.

40 3. Cam device for the control of a mechanism, comprising a disc, a rocking lever adapted to cooperate with said disc and to be operatively connected with said mechanism to be controlled, a number of axle-pins one 45 of which is rotatably and slidably supported by said lever while the others are likewise

supported by said disc near the periphery thereof, an eccentric part on each of all said axle-pins, a roller mounted loose on said eccentric part, the roller thus supported by 50 said lever being adapted to engage the rollers supported by said disc and means for maintaining each axle-pin in various angular positions for which said rollers protrude to a variable amount from the periphery of 55 said disc and the edge of said lever.

4. Cam device for the control of a mechanism, comprising a disc, a rocking lever adapted to cooperate with said disc and to be operatively connected with said mechanism to be controlled, a number of axle-pins one of which is rotatably and slidably supported by said lever while the others are like-wise supported by said disc near the periphery thereof, an eccentric part on each of all said axle-pins, a roller mounted loose on said eccentric part, the roller thus supported by said lever being adapted to engage the rollers supported by said disc, a cross pin 60 provided on each axle-pin, slots in said disc 65 and lever and wherein said cross-pins are respectively adapted to engage and springs acting axially upon said axle pins and whereby said cross-pins are urged into said slots for holding said axle-pins in position. 70

5. In a cam device as claimed in claim 3, the further feature residing in that the roller supported by said lever is adapted to assume intermediate angular positions between the positions of maximum and minimum 75 projection from the edge of said lever.

6. In a cam device as claimed in claim 4 the further feature residing in that the lever is provided with a plurality of slots at a predetermined angle with each other for the cross-pin of the axle-pin of the roller supported by said lever. 80

In testimony whereof we have signed our names to this specification.

GEORGES EZBELENT.
ROGER EZBELENT.
